UNITED STATES PATENT OFFICE.

JOSEPH D. GILLAN, OF PROVIDENCE, RHODE ISLAND, ASSIGNOR TO WARWICK
STERLING COMPANY, OF PROVIDENCE, RHODE ISLAND, A CORPORATION OF
RHODE ISLAND.

CIGARETTE-CASE.

1,174,406.

Specification of Letters Patent. Patented Mar. 7, 1916.

Application filed September 17, 1914. Serial No. 862,136.

To all whom it may concern:

Be it known that I, JOSEPH D. GILLAN, a citizen of the United States, and resident of Providence, in the county of Providence and 5 State of Rhode Island, have invented certain new and useful Improvements in Cigarette-Cases, of which the following is a specification.

This invention relates to improvements in 10 cases for carrying cigarettes or other similar articles and has for its object to provide an improved form of casing having a carrier, frame or holder mounted to fold between the covers of the casing for receiving 15 the contents, the carrier being adapted to be positioned between the edges of the partially opened covers to place the contents in position for easy access.

With these and other objects in view, the 20 invention consists of certain novel features of construction, as will be more fully described, and particularly pointed out in the appended claims.

In the accompanying drawings: Figure 1 25 is a perspective view showing the carrier as swung outward and set between the partially opened covers to place the contents in position for easy access. Fig. 2 is a perspective view of the casing in open position, 30 one of the members of the carrier being folded into one of the covers and the other member of the carrier thrown back into position to receive the cigarettes between them. Fig. 3 is a perspective view of the carrier 35 as loaded and folded into one of the concaved covers. Fig. 4 is a sectional edge view showing the casing covers hinged together and in closed position also showing the carrier members hinged together and one 40 of the members hinged to one of the casing covers. Fig. 5 is an enlarged view showing the spring at the hinge of the carrier members which exerts a slight pressure on one of said members to hold the cigarettes be- 45 tween them.

Referring to the drawings:—my improved cigarette casing may be made of any suitable material, but is preferably constructed of metal and comprises two lids 10 and 11 50 preferably of a concavo-convex shape hinged together at 12 on one edge, and provided on its opposite edge with a spring catch 13 adapted to lock the lids in closed position.

A feature of my invention is the provision 55 of what I term a carrier or holder, which is

constructed of two members 14 and 15 hinged together at 16, the hinge being preferably provided with a spring 17 (see Figs. 2 and 5) whereby a slight pressure is exerted on member 15 to hold it normally in 60 closed position to better retain the contents between them. The member 14 is hinged at 18 to the lid 11 whereby the leaves or members of the carrier may be folded together and lie in the concaved portion of this lid 11. 65

In operating my improved cigarette holder the lid 10 is opened into position illustrated in Fig. 2 and the member 15 of the carrier is swung back against the tension of its closing spring 17 to permit the case 70 to be loaded. This member 15 is then permitted to close down over the contents, as illustrated in Fig. 3, after which the lid 10 may be closed over the whole and the case stowed away in the pocket of the user, the 75 same as any case of this character, but in some instances it is desired to open and place the case on a table to bring the cigarettes in position for easy access. To do this, it is only necessary to place the lid 10 down- 80 ward to form a base, open the lid 11 and swing the carrier on its hinge 18 outward from the upper lid 11 so that its free edge will rest against that of the base lid, and in engagement with the retaining block 19. 85 In this position the two lids are held open and the whole contents of the case is brought out and forward into plain sight and within convenient reach of the users.

In order to close the case it is only nec- 90 essary to turn the case over, swing the carrier back away from the retaining block 19 and close and latch the covers.

The device is very practical in construc- 95 tion and by its use the whole contents of the casing may be readily placed in position for inspection and easy access.

I claim:

1. A cigarette case comprising a receptacle formed of two lids hinged together at 100 one edge, a holder located within the in- closure and formed of two members hinged together at one edge, the hinge of the holder being adjacent the hinge of the receptacle, the edge of one holder member opposite the 105 hinge of the holder, being hinged to the corresponding edge of one of said lids.

2. A cigarette case comprising a receptacle formed of two lids hinged together at one edge, a holder located within the in- 110

closure and formed of two members hinged together at one edge, the hinge of the holder being adjacent the hinge of the receptacle, the edge of one holder member opposite the 5 hinge of the holder, being hinged to the corresponding edge of one of said lids, and means carried by the other lid for engaging the connected ends of the holder members,

when the holder has been swung outwardly on its hinged connection with the receptacle. 10

In testimony whereof I affix my signature in presence of two witnesses.

JOSEPH D. GILLAN.
